A. F. CARLIN.

TOY PISTOL.

APPLICATION FILED AUG. 19, 1919.

1,346,938.

Patented July 20, 1920.

Inventor

Arvid F. Carlin
By his Attorney

Edgar State Co.

UNITED STATES PATENT OFFICE.

ARVID F. CARLIN, OF NEW YORK, N. Y.

TOY PISTOL.

1,346,938.

Specification of Letters Patent.

Patented July 20, 1920.

Application filed August 19, 1919. Serial No. 318,482.

To all whom it may concern:

Be it known that I, ARVID F. CARLIN, a citizen of the United States, and residing at New York, in the county of New York and State of New York, have invented certain new and useful Improvements in Toy Pistols, of which the following is a specification, such as will enable those skilled in the art to which it appertains to make and use

10 the same.

This invention relates to toy pistols, and the object thereof is to provide a device of this class which is made from sheet metal folded into the desired form and which is designed to shoot or project small spherical or approximately spherical bodies such as peas; and with this and other objects in view the invention consists in a device of the class and for the purpose specified which is 15 simple in construction and operation and efficient in use.

20 The invention is fully disclosed in the following specification, of which the accompanying drawing forms a part, in which the separate parts of my improvement are designated by suitable reference characters in each of the views, and in which:—

Figure 1 is a side view of a toy pistol involving my invention;

Fig. 2 a transverse section on the line 2—2 of Fig. 1 and on an enlarged scale;

Fig. 3 a central longitudinal section through the pistol;

Fig. 4 a plan view looking in the direction of the arrow 4 of Fig. 1 but showing only a part of the construction;

Fig. 5 a partial section on the line 5—5 of Fig. 3; and,

Fig. 6 a partial section on the line 6—6 of Fig. 3.

40 In the practice of my invention, I provide a pistol casing 10 consisting of a barrel portion 11 and a hollow handle portion 12, and these parts are formed integrally and preferably from a single sheet of metal bent into the desired form, the free edges of the barrel portion 11 being crimped together as shown at 13 while the handle portion 12 or the open edges thereof are crimped together as shown at 14.

50 The barrel portion 11 extends into the handle portion 12 as shown at 15, and a spiral spring 16 is mounted in the part 15 and held in place by inwardly directed members 17 stamped from the opposite sides 18 and 19 of the handle portion 12.

A spring trigger member 20 is pivoted to and between the sides 18 and 19 of the handle portion 12, as shown at 21 and the end portion 22 of said member is adapted to bear 60 on the bottom of the handle portion 12, while the other or free end 23 of said member is provided with an approximately circular hammer head 24 outwardly of which is a finger piece 25. It will be noted that the 65 extension 15 of the barrel 11 is formed by inwardly directed arc-shaped beaded portions 26 in the separate sides 18 and 19 of the handle portion 12, and the trigger member 20 is reduced as shown at 27 below the hammer 70 head 24 to fit in and operate between the beaded portions 26. The top of the barrel portion 11, or the extension 15 thereof is provided with an elongated aperture 28 enlarged at one end as shown at 29, and the 75 finger piece 25 of the trigger member 20 is adapted to pass through and operate in said apertures as illustrated in Figs. 3, 4 and 5 of the drawing.

A trigger catch device 30 is stamped from 80 the side 18 of the handle portion 12 as clearly shown in Fig. 3 and bent inwardly to a slight extent to give it a spring action, and the free end of said device is provided with an inwardly depressed portion 31 adapted to 85 engage the trigger member 20 as indicated in dotted lines in Fig. 3, to hold said trigger member in such position against the tension of the spring 16.

I also stamp from the side 19 of the handle 90 portion 12 a trigger releasing member 32 which is bent inwardly as shown at 33 and adapted to operate in connection with the trigger catch device 30 to disengage the same, or the part 31 thereof, from said trigger member.

95 It will be seen from the foregoing that my improved toy pistol is made from a single sheet of metal fashioned into the desired form, and the only parts employed 100 in connection therewith are the trigger member 20 and spring 16. It will, therefore, be seen that the pistol may be made at a very reasonable price by reason of its simplicity in construction as well as the method of 105 making the same.

The operation of the pistol will be readily understood from the foregoing description when taken in connection with the accompanying drawing and the following statement. The normal and inoperative position of the parts is that shown in full lines in the

drawing, and when it is desired to project a spherical body, such for example as a pea from the pistol, the trigger member 20 is drawn backwardly into the position indicated in dotted lines in Fig. 3 by grasping the finger piece 25. A pea or similar article is then dropped into the barrel portion 11 through the aperture 29 just forwardly of the trigger member 20, after which the trigger releasing member 32 is moved inwardly by hand to move the trigger catch device 30 outwardly to release the trigger member 20, and the spring 16 as well as the spring action of the trigger member will advance said trigger member forwardly into the position shown in full lines in Fig. 3 and project the pea or other article from the pistol. The above operation may be repeated as often as desired, and it will also be understood that the pea or other projectile may be placed in position in the barrel portion 11 by passing the same thereinto through the open or discharge end of said barrel portion. It will also be understood that while I have shown certain details of construction for carrying my invention into effect, I am not necessarily limited to these details, as various changes therein and modifications thereof may be made, within the scope of the appended claims, without departing from the spirit of my invention or sacrificing its advantages.

Having fully described my invention, what I claim as new and desire to secure by Letters Patent, is:—

- 35 1. A toy pistol of the class described made from a single sheet of metal fashioned to form a barrel portion and a handle portion, means for securing and holding said barrel and handle portions in position, a trigger member movably mounted in said handle portion, and a movable catch device formed integrally with said handle portion and adapted to operate in connection with said trigger member.
- 40 2. A toy pistol of the class described made from a single sheet of metal fashioned to form a barrel portion and a handle portion, means for securing and holding said barrel

and handle portions in position, a trigger member movably mounted in said handle portion, a catch device formed integrally with said handle portion and adapted to operate in connection with said trigger member, and a trigger releasing member formed from said handle portion and adapted to operate in connection with said catch device.

3. A toy pistol of the class described formed from sheet metal and comprising a barrel portion and a handle portion integral therewith, the barrel portion extending into said handle portion, a spiral spring mounted within the extension of said barrel portion the top of said extension being provided with an aperture, a trigger member mounted within the handle portion and adapted to pass through said aperture and in connection with which said spring operates, and a catch device in said handle portion adapted to operate in connection with said trigger member in one position thereof.

4. A toy pistol of the class described formed from sheet metal and comprising a barrel portion and a handle portion integral therewith, the barrel portion extending into said handle portion, a spiral spring mounted within the extension of said barrel portion the top of said extension being provided with an aperture, a trigger member mounted within the handle portion and adapted to pass through said aperture and in connection with which said spring operates, a catch device in said handle portion adapted to operate in connection with said trigger member in one position thereof, and means in said handle portion operating in connection with said catch device for releasing said trigger member.

In testimony that I claim the foregoing as my invention I have signed my name in presence of the subscribing witnesses this 15th day of August, 1919.

ARVID F. CARLIN.
